Application December 19, 1938, Serial No. 246,720
In France February 16, 1938

9 Claims. (Cl. 102—8)

This invention relates to improvements in or modifications of the device for the protection of the ground of military operations by means of mines or other like appliances, described in the specification of U. S. Letters Patent No. 1,28,839, in which the firing mechanism of each of the protective appliances is associated with a pull or push member, such as a cable or other like member, one of the ends of which produces directly or indirectly, for example by means of a trip device, the movement of the movable member of the firing mechanism, the device being characterised in that it comprises a cable guided in a sheath constructed so as to be capable of elongating under the effect of a deformation, one of the ends of one of the said elements (cable or sheath) being fixed to the movable member of the firing mechanism or to a part retaining the said member, while the corresponding end of the other element (sheath or cable) is fixed to or supported on the said appliance, the other two ends of the said associated elements being secured together or having, in a second appliance coupled to the first, the same relative dispositions or inverse dispositions as in the first appliance.

In the hereinbefore mentioned specification here are described in addition and shown by way of example, different forms of construction of the invention, in which forms one of the ends of the cable is fixed to the movable member of the firing mechanism or to a part retaining the said member, while the corresponding end of the sheath is fixed to or supported on the appliance itself. The elements forming the sheath may have extremely varied forms.

One of the present improvements relates to a particular form of construction of the invention described in the hereinbefore mentioned specification, and to a particular form of arranging the deformable sheath employed for effecting the firing.

In the form of construction under consideration, one of the ends of the cable is secured to the appliance to be exploded, while the end of the sheath exerts a push on the movable member of the firing mechanism.

As to the particular arrangement of the sheath referred to above, it is characterised by the introduction at various points along the said sheath of elongation control groups particularly favourable for the operation of the device.

These groups comprise a certain number of adjacent beads, each of which has the shape of a sort of biconvex lens, and between the edges of

which are disposed rings made of an extremely ductile metal, annealed aluminium for example, the said rings acting at the desired moment as forcing members for obliging the aforesaid lens-shaped beads to move away from one another and to produce an appreciable elongation of the sheath.

Another and final improvement according to the present invention relates to various particular devices for the relative adjustment of the cable and its sheath.

The different forms of construction just referred to are shown diagrammatically in the accompanying drawing, but these forms of construction may be modified in their details or may be completed by any suitable accessory device without departing from the invention.

Referring to the drawing,

Figure 1 shows a diametrical section of the firing device and of one of the elongation control groups of the sheath.

Figure 2 represents a cross-section on the line II—II of Figure 1.

Figures 3 and 4 represent sections of two devices for the relative adjustment of the cable and its sheath by a take-up screw.

Figures 5 and 6 show two sections of a device for the relative adjustment of the cable and its sheath by means of a sort of wedge.

As will be seen in Figure 1, the form of construction according to the present invention comprises as firing mechanism a fuse, the head 1 of which is screwed on the appliance 2 to be exploded and carries a fixed percussion-cap 3 mounted in a likewise fixed percussion-cap carrier 4 which is struck at the moment of firing by a striker 5.

The latter, which is normally fixed by means of a pin 6, is subjected to the action of a thrust spring 7 bearing on a fixed part 8 and also to the action of a sort of fork 9, the arms 10—10 of which pass freely through suitable orifices 11 provided in the fixed part 8, against which is applied the end 12 of the deformable external sheath 13 surrounding the retaining cable 14.

The end 15 of the latter is secured in any suitable manner to the fixed part 8 and consequently to the fuse body 1.

A flanged socket 16, for example, is employed for this purpose.

The operation of the device is extremely simple to understand.

When, due to its being crushed at the moment of the passage of a tank, the sheath 13 undergoes elongation relatively to the constant

length cable 14 which it surrounds, its end 12 pushes the fork 9 towards the interior of the fuse.

The arms 10 of the said fork in their turn push the striker 5 and produce the shearing of the retention pin 6.

As soon as the latter is fractured, the spring 7 suddenly relaxes and drives the striker violently against the percussion-cap 3, thus producing the ignition of the explosive charge.

In the upper part of Figure 1 is shown one of the different elongation control groups provided along the sheath.

The latter, which comprises in the vicinity of the fuse a flexible part 17, also includes a series of beads 18, 19, etc., and, at spaced points, groups of four beads 20 of large diameter having the form of biconvex lenses, between the edges of which are disposed rings 21 made, as stated hereinbefore, of an extremely ductile metal, such as, for example, annealed aluminium. As shown, the outer surfaces of the rings 21 extend beyond the peripheries of the lenticular beads 20 so that, when a tank or other heavy object passes over a portion of the sheath embodying one of the elongation control groups, the rings 21 will be crushed and portions thereof will be forced between and spread the beads 20, thereby elongating the sheath and igniting the explosive charge in the manner above described.

The end 22 of the cable 14 has an expanded form which prevents it from entering the interior of the last bead 23 of the sheath.

If desired, a flexible sheath element 24 may be interposed between the bead 23 and the other beads of the sheath.

If it is desired to be able to adjust the length of one of the elements, cable or sheath, relatively to the other, so as to adjust at the same time the application of the end 12 of the sheath against the part 9, it is possible to employ one of the devices shown respectively in Figures 3, 4, 5 and 6.

In the form of construction shown in Figure 3, there are provided, between the bead 23 and the flexible sheath element 24, two adjacent beads 25 and 26, the first of which, the bead 25, forms a sort of internally screw-threaded sleeve, while the second, the bead 26, comprises a screw-threaded body 27 adapted to screw in the internal screw-thread of the bead 25.

It is easy to understand that by screwing the bead 26 more or less in the bead 25, the assemblage formed by these two members is given a greater or lesser length, the consequence of which is to increase or reduce, as desired, the total length of the sheath.

In the form of construction shown in Figure 4, the bead 26 is screwed directly in the end lenticular bead 20 of one of the crushing control groups, which lenticular bead is provided for this purpose with an internal screw-thread 28.

In the form of construction shown in Figures 5 and 6, of which the first is a section on the line V—V of Figure 6, while the second is a sectional plan of the part of the mechanism situated below the plane VI—VI of Figure 5, the adjustment of the length of the sheath relatively to that of the cable 14 is effected by means of a key 29 having the form of a fork, the arms 30 of which act as forcing wedges between the end bead 23 and the preceding bead 31.

I claim:

1. In apparatus of the character described for protecting the ground of military operations

which includes an explosive device and means for exploding the same comprising a sheathed cable adapted to lie on or just beneath the surface of the ground, the sheath of said cable being so constructed and arranged as to elongate when deformed by the passage thereover of a tank or other heavy object and having its outer end fixed relatively to the outer end of said cable, the combination of means for securing the inner end of said cable to said explosive device, a firing mechanism mounted within said device having one element fixed relatively to the latter and another element movable relatively thereto, a spring tending to move said movable element into firing position, frangible means normally restraining said movable element from movement under the influence of said spring, and a second movable element housed within said explosive device in abutting relation with said first movable element, said second movable element being so constructed and arranged as to receive the inward thrust of the inner end of said cable sheath when the latter is elongated and to transmit said thrust to said first movable element, whereby elongation of said sheath may effect a fracture of said restraining means and permit said spring to move said first movable element into firing position.

2. In a fuse of the type adapted to be fired by relative movement between the inner ends of a non-extensible cable and a surrounding sheath which are adapted to lie on or just beneath the surface of the ground, the sheath being so constructed and arranged as to elongate when de-

formed by the passage thereover of a tank or other heavy object, the outer ends of said cable and sheath being fixed relatively to one another, the combination of a fuse body, a member mounted in said fuse body to which the inner end of said cable is permanently secured, said member being incapable of outward movement relatively to said fuse body, a percussion cap fixed in said fuse body, a striker member movably mounted in said fuse body, a spring operatively interposed between said fuse body and said striker member tending to move the latter into firing contact with said percussion cap, yieldable means normally restraining said striker member from such movement under the influence of said spring, and a thrust element mounted in said fuse body for inward movement therein and normally having its inner end in abutment with the outer end of said striker member, the inner end of said cable sheath abutting against the outer end of said thrust element, whereby the inward movement of the inner end of said sheath upon elongation is transmitted by said thrust element to said striker member to overcome said yieldable restraining means and permit said spring to move said striker member into firing contact with said percussion cap.

3. A fuse according to claim 2 wherein the member to which the inner end of said cable is secured is positioned between said striker member and the outer end of said thrust element and is provided with an opening through which passes the striker abutting portion of said thrust element.

4. A firing mechanism according to claim 9 wherein said adjusting means consists of a pair of inter-threaded members surrounding said cable and abutting respectively said bead-like member and the outer end of said sheath.

5. A firing mechanism according to claim 9 wherein said adjusting means consists of a mem-

ber surrounding said cable with its outer end abutting said bead-like member and its inner end having threaded engagement with the outer end of said sheath.

6. A firing mechanism according to claim 9 wherein the outer end of said sheath consists of one of said elongation control devices, and wherein said adjusting means consists of a member surrounding said cable with its outer end abutting said bead-like member and its inner end having threaded engagement with the outermost lenticular element of the elongation control device forming the end of said sheath.

7. A firing mechanism according to claim 9 wherein said adjusting means consists of a forked wedge member removably straddling said cable with its wedge-forming surfaces abutting respectively said bead-like member and the outer end of said sheath.

8. In a firing mechanism for explosive devices of the type comprising a non-extensible cable and a surrounding sheath which are adapted to lie on or just beneath the surface of the ground, the sheath being so constructed and arranged as to elongate when deformed by the passage thereover of a tank or other heavy object, a plurality of elongation control devices interposed in said sheath at spaced points along its length, each consisting of a plurality of lenticular elements threaded on said cable of greater diameter than the remainder of said sheath, and rings of ductile metal surrounding and substantially spaced from said cable, said rings being interposed between and supported on the peripheral portions of the lenticular surfaces of adjacent elements with their outer surfaces lying beyond the peripheries of said elements, said rings being

adapted to force said lenticular elements apart, and thereby to elongate the sheath, when crushed by the weight of an overpassing object.

9. A firing mechanism for explosive devices of the character described comprising a flexible, non-extensible cable, a flexible sheath surrounding said cable and adapted to lie on or just beneath the surface of the ground, said sheath being so constructed and arranged as to elongate when deformed by the passage thereover of a tank or other heavy object and comprising a plurality of elongation control devices interposed therein at spaced points along its length, each of said devices consisting of a plurality of lenticular elements threaded on said cable and of greater diameter than the remainder of said sheath, and rings of ductile metal surrounding and substantially spaced from said cable, said rings being interposed between and supported on the peripheral portions of the lenticular surfaces of adjacent elements with their outer surfaces lying beyond the peripheries of said elements, said rings being adapted to force said lenticular elements apart, and thereby to elongate the sheath, when crushed by the weight of an overpassing object, the inner ends of said cable and sheath being associated with the device to be exploded and the outer end of said cable extending beyond the corresponding end of said sheath and having a bead-like member secured thereto, and means of variable effective length in an axial direction interposed between said bead-like member and the outer end of said sheath for adjusting the distance between the outer ends of said cable and sheath.
